UNITED STATES PATENT OFFICE.

JUSTUS H. RUDOLPH, OF NEW YORK, N. Y., ASSIGNOR TO THE SPECIALTY MANUFACTURING COMPANY, OF SAME PLACE.

REVERSIBLE BLACKBOARD.

SPECIFICATION forming part of Letters Patent No. 301,392, dated July 1, 1884.

Application filed October 23, 1883. (No model.)

To all whom it may concern:

Be it known that I, JUSTUS H. RUDOLPH, of New York, in the county of New York and State of New York, have invented a new and useful Improvement in Slates and Blackboards; and I do hereby declare that the following is a full, clear, and exact description of the same.

My invention relates to blackboards, and has for its object to simplify and cheapen the general construction of such articles, as the blackboards commonly used are very heavy and clumsy, and in most cases it is necessary to secure them rigidly in place upon the wall when a surface of considerable extent is required.

My invention consists in a reversible pack or crayon-holder, adapted to be used as such on both sides of the blackboard; and, further, in the improved construction of my blackboard in all its parts, as hereinafter fully described and claimed.

In the drawings, Figure 1 is a side elevation of a portable blackboard with my improvements. Fig. 2 is a section on line $x-x$ of Fig. 3. Fig. 3 is a front view. Fig. 4 is a modification representing a wall-board embodying my improvements. Fig. 5 also represents a separate view of a modification.

The frame A of the blackboard, as shown in Fig. 3, is composed of side strips, 1 1, which are preferably mortised into top and bottom strips, 2 2, the ends of which extend a little beyond the side strips to improve the appearance. Above the top strip, 2, and below the ends of the side strips, 1, I place another strip, 3, and support it upon the strip 2 by blocks 4 4, to which it may be nailed, the strip 2 being secured to said blocks in a like manner. Under the bottom strip, 2, I place a strip similar to that just described, and secure it in the same way. Within the space formed by the strips 1 2 2 is placed the material composing the board, it being either of slate or composition, and fitting snugly therein, where it may be held by beads, as shown, or in any other well-known way.

The arrangement of the legs is shown in Fig. 1. These consist of long and short legs, (marked, respectively, 6 6 and 7 7.) The long legs 6

are pivoted upon the outside of the side pieces, 50 1 1, at a suitable height, by means of screws passing through the said legs and entering the frame of the board. The short legs 7 7 are hinged to the legs 6 6 at the point 8 in such a manner as to close up against such legs when desired. These legs 7 7 are also secured to the lower ends of extension-pieces 5 5 of the side pieces of the frame by means of screws 9 9, which pass through slots 10 in said extensions and enter the legs at the point 11, the 55 said slots 10 permitting the slight vertical movement of the screws or pins 9 9 when the legs are being folded.

The crayon or pencil holder is shown more particularly in Fig. 2. It consists of two light 65 pieces of any suitable wood joined at right angles and closed at the end. It may have a rod of wood or metal running along the bottom and journaled in bearings within the extensions 5 5 of the side pieces below the strengthening-pieces 3, so as to allow an easy movement thereon; or it may be hung on pins projecting from the extension-pieces of the frame. This construction is adapted to be used with a board having two faces, or blacked on both 70 75 sides, and enables the operator to turn the holder on its pivots to whichever side he may be writing upon.

In Fig. 4 I have represented a wall-board having my improvements. The frame of this 80 board is similar in all respects to the form just described, with the exception of the extension-pieces, which are not necessary in this case, as no legs are necessary, the board being adapted to be supported against the wall. The 85 pocket or crayon-holder in this case is pivoted upon screws passing through the side pieces and entering the ends of the holder. This holder is also made double, as in the former case, and can be used for the same purpose 90 upon either side of the board. When used upon one side, the upright portion fits closely out of the way, to all practical purposes.

When it is desired to use my holder upon 95 stationary wall-boards, or boards blacked upon one side only, I form my holder as shown in Fig. 5, taking only one-half of the holder

before described, and pivoting it in the manner shown in the figure, so that the holder, when not in use, may be folded up against the frame, out of the way.

5 It will be observed that the different parts of my improved slate-frame are mortised together, which is a very economical as well as durable way, and it dispenses with the use of glue, &c., which is objectionable in such devices, as it is liable to become wet by the use of the sponge in cleaning the slate, and thereby lose its binding effect.

10 The described arrangement of the legs in the form first alluded to is very simple and effective, and allows the front or short legs to fold up against the sides of the frame and in line with it, and the back or long legs fold up against these short legs, making a very compact device when folded, and capable of being 15 stowed away in a very small space.

20 Having thus described my invention, what I claim is—

1. A slate or blackboard composed of the frame A, containing the slate, the legs 6 6, pivoted on the said frame, and legs 7 7, hinged to 25 the said legs 6 6 and adjustably connected to the frame A, substantially as described.

2. The combination, with a slate, blackboard, or the like, of a reversible crayon or pencil holder adapted to be used upon either side at 30 will, substantially as described.

3. The combination, with a slate or blackboard, of a reversible crayon-holder, substantially as described.

In testimony whereof I have signed my name 35 to this specification in the presence of two subscribing witnesses.

JUSTUS H. RUDOLPH.
